UNITED STATES PATENT OFFICE.

JOSEPH V. SANTRY, OF BOSTON, MASSACHUSETTS, ASSIGNOR TO CHARLES W. E. CLARKE, OF BROOKLINE, MASSACHUSETTS.

HEATING AND POWER-PRODUCING SYSTEM.

1,154,210.

Specification of Letters Patent. Patented Sept. 21, 1915.

Application filed February 2, 1915. Serial No. 5,801.

To all whom it may concern:

Be it known that I, JOSEPH V. SANTRY, a citizen of the United States, residing at Boston, in the county of Suffolk and State of Massachusetts, have invented certain new and useful Improvements in Heating and Power-Producing Systems, of which the following description, in connection with the accompanying drawings, is a specification, like reference characters on the drawings indicating like parts in the several figures.

It has long been a common practice to use the exhaust steam from a steam engine for heating purposes. In the usual arrangement, the steam heating system is connected with the exhaust port of the engine and a relief valve is employed in the system to permit the escape of steam when the pressure rises above the desired point. The steam escaping through the relief valve is, of course, wasted; and a serious objection to an arrangement of this kind is that the quantity of steam delivered to the heating system is controlled by the service requirements of the engine rather than by the demands of the heating system; and accordingly in mild weather or when unusual service is required of the engine a very substantial percentage of the exhaust steam is wasted. On the other hand, this arrangement frequently is valuable from the standpoint of economy, particularly where the demand for exhaust steam approximates the amount of steam available from the engine.

The present invention aims to devise a system of the general character above described which will avoid the disadvantages of this system while still retaining its advantages. It is proposed to accomplish this object by controlling the flow of steam to the engine in accordance with the requirements of the heating system. In some cases this arrangement will not interfere materially with the service required from the engine but where this is not the case it is proposed to operate the engine in parallel with another source of power and to control these two sources of power in the manner required to give the desired service. Provision also is made for maintaining the service required from the heating system when, for any

reason, the engine fails to supply it with the quantity of steam necessary to meet the demands of this service.

55

The invention will be readily understood from the following description, when read in connection with the accompanying drawings, in which—

Figure 1 is a view somewhat diagrammatic, of a system embodying the invention; Fig. 2 is a side elevation of a valve used in the system shown in Fig. 1; Fig. 3 is a central, vertical, sectional view of the valve shown in Fig. 2; and Fig. 4 is a view 60 similar to Fig. 3 of a slightly modified construction of valve which also is used in the system.

Referring now to the drawings, 2 indicates a main steam supply pipe leading from the boiler equipment of the plant in which the installation is made. Two steam engines of the turbine type are indicated, respectively, at A and B and are both directly connected to a common load indicated in the drawings as an alternating current generator G. The turbine A has its admission port connected through a conduit 4 and hand valve 6 to the main steam supply pipe 2 and its exhaust port may be connected 65 through the conduit 8 to a condenser. The other turbine B has its admission port connected through a conduit 10 and a hand valve 12 to the main steam supply 2 and has its exhaust port connected to the main 70 supply pipe 14 of the heating system, parts of which are indicated diagrammatically at 16. The turbines A and B may be standard machines equipped with the usual speed governors and will, of course, be selected to meet 75 the requirements of any particular installation to be made. The heating system is directly connected through the conduit 18, the reducing valve 20 and the hand valve 22 with the main steam supply pipe 2.

90
95
100
The reducing valve may be of any convenient type but for the purpose of fully disclosing the invention, a valve of a common construction is shown in Figs. 2 and 3. This valve comprises a casing having an intake port 24, an outlet 25 and a valve seat 26, a valve 27 being mounted on a stem 28 for movement into and out of engagement with said seat. The casing also is provided with

a chamber 29 which communicates with the inlet 24 and the lower end of this chamber is closed by a flexible diaphragm 30 which covers the whole lower end of the casing 5 and is clamped to the casing by means of a ring 31. The margin of this diaphragm projects beyond the outline of the casing and this free marginal edge of the diaphragm is clamped between a ring 32 and 10 the margin of a head 33 that overlies the bottom of the casing and is provided with a chamber 34. The ring 32 and head 33 are connected to the casing only by means of the diaphragm. Communication is provided 15 between the chamber 34 and the outlet port 25 through a nipple 35 that extends through the diaphragm 30 and opens at one end into the chamber 34 and at its opposite end into a passage or duct 39 that leads to 20 the outlet 25. The valve stem 28 is threaded through a central aperture in the head 33 and carries a collar 36 pinned thereto and bearing on the outer face of the head and another collar 37 which also is pinned to the 25 stem inside the casing and bears against a washer 38 that clamps the middle portion of the diaphragm 30 to a boss or projection on the inner side of the head 33. The area of the diaphragm 30 exposed to the action of 30 the steam on the inlet side of casing is the same as the area of the valve 27 which also is exposed to this pressure. Consequently, this pressure does not tend to move the valve 27 in either direction. The inner side of the 35 head 33 is exposed to the pressure of the steam on the outlet side of the valve, this pressure being admitted through the nipple 35 and duct 39 and tending to hold the valve 27 on its seat 26. This tendency is opposed 40 by a spring 40 outside the casing which has one end connected to an eye bolt 41 adjustably mounted in a stationary part of the valve casing and its other end connected to one end of a lever 42 fulcrumed on a stationary 45 part 43 of the casing and bearing at a point between the spring and its fulcrum against the lower end of the valve stem 28.

It will now be evident that, assuming the parts to be connected as shown in Fig. 1 and 50 steam to be admitted to the inlet 24, it will pass through the valve out of the outlet 25 and into the conduit 18 to the heating system, the spring 40 at this time acting to hold the valve open. As soon, however, as the 55 pressure of the steam in the outlet side of the valve has raised to a point predetermined by the adjustment of the spring 40, this pressure acting on the head 33 will move the head downwardly, carrying the valve 60 stem with it and thus seating the valve and preventing any further flow of steam. The valve then will tend to take such a position 65 that it will maintain a substantially constant pressure in the outlet side 25 of the casing, admitting just enough steam, when this

pressure falls below a predetermined point, to bring the pressure up again to that point. A similar valve is connected in the steam line leading to the turbine B; but in this case there is no connection between the outlet 70 port 25 and the chamber 34 in the head 33. Instead of this arrangement, a small pipe 46, leading from the main 14 of the heating system, is tapped into the wall of a duct 47 which communicates through the nipple 35 75 with the chamber 34, see Fig. 4. This arrangement, therefore, instead of making the valve responsive to pressure changes in its outlet, makes it responsive to pressure changes in the heating system. 80

The valve 45 preferably is set to maintain the required pressure on the heating system, this setting being made according to a scale 48 and an indicator 49 with which valves of this character usually are 85 equipped, as indicated in Fig. 2; but the valve 20 is set to operate at a lower pressure than the valve 45. It is preferred also to set the governor for the turbine B for a higher speed than the governor of the turbine A. Assuming now that the hand valves 6, 12 and 22 are all open, that normal steam pressure is maintained on the steam supply system and that the turbines A and B are in operation, the turbine B will tend to take 90 the load away from the turbine A because its governor is set to operate at a higher speed. If the load is such that the turbine B can carry it at the required speed without the aid of the turbine A, then the governor of the 95 turbine A will cut the latter turbine out of operation and it will run idly. The exhaust steam from the turbine B will be delivered to the main supply pipe 14 of the heating system. Since the valve 45 is responsive to 100 pressure changes in the heating system and since this valve controls the flow of steam to the turbine B, it will vary the supply of steam to the turbine in accordance with the requirements of the heating system. That 105 is, if the pressure in the heating system falls below a value determined by the adjustment of the spring 40, this spring will open the valve wider and admit more steam to the turbine, consequently supplying more steam 110 to the heating system and thereby raising the pressure in the heating system. This increase in pressure, however, will be transmitted through the pipe 46 to the chamber 34 and will operate on the head 33 and the 115 valve stem 45 to close the valve more or less depending on the degree of rise in pressure in the heating system. In other words, this valve will automatically vary the supply of steam to the turbine B in such a manner as 120 to maintain a substantially constant steam pressure on the heating system. If the load increases to such a value that the turbine B cannot carry it at the required speed, the 125 consequent reduction in speed will cause the 130

governor of the turbine A to cut in this turbine allowing it to take enough of the load to maintain the generator speed at substantially the speed for which the governor of the turbine A is set; but as soon as the load drops off again, the consequent increase in speed will cause the governor of the turbine A to cut this turbine out again and permit the turbine B to carry all the load.

10 The governor of the turbine B of course acts entirely independently of the valve 45. Accordingly, if the load decreases so far that the governor of the turbine B cuts down the flow of steam through this turbine to such a 15 point that it passes an insufficient quantity of steam to maintain the desired pressure on the heating system, then the valve 45 will be unable to remedy the deficiency and when the pressure has dropped to a point predetermined by the adjustment of the spring 40 of the valve 20, this valve will be opened and will admit steam directly from the supply main 2 to the heating system, the steam pressure, however, being reduced as it passes 20 through the valve 20 to substantially the pressure which normally is maintained on the heating system. In case the demand for 25 exhaust steam falls off, the turbine B of course will not carry its proportion of the load, due to the fact that the heating system will not allow it to pass the amount of steam required for this purpose. This of course tends to reduce the speed of the unit and in turn to throw the load on to the turbine A. 30 The turbine A will be designed to develop sufficient power to carry the entire load alone.

35 The pressure which it is desired to have maintained on the heating system varies in different plants but usually is somewhere between ten and fifty pounds. Assuming for the moment that it is twenty pounds and that the steam pressure in the main supply pipe 2 is two hundred pounds, it will be evident that the turbine B is operating under 40 a pressure range of from two hundred to twenty pounds. Considerations of economy, therefore, may require that a different type of steam engine than that shown be used 45 over this range while another type be used at A to operate in parallel with the engine B. The selection of the proper steam engines for any particular installation obviously is a matter of judgment to be settled 50 according to the requirements of each particular case. The particular source of power used in parallel with the engine B also will vary with the character of the service required from the engine and the nature of the 55 load that it carries.

60 It is obvious that the exhaust steam from the turbine B may be used for other purposes than heating without departing from the spirit or scope of this invention. A heating system has been specifically mentioned

in this specification because this is a very common use made of exhaust steam. It is desired, however, that this term be regarded as illustrative rather than limiting, since obviously the system is equally applicable to 70 cases in which other uses are made of the exhaust steam than that of heating.

Having thus described my invention, what I claim as new and desire to secure by Letters Patent of the United States is:

1. The combination of a steam supply, a steam heating system, a steam engine connected to said supply and said heating system to receive steam from said supply and deliver exhaust steam to said heating system, 80 means operative automatically to control the flow of steam to said engine in accordance with the requirements of the heating system, and a source of power operating in parallel with said engine.

2. The combination of a steam supply, a steam heating system, a steam engine connected to said supply and said heating system to receive steam from said supply and deliver exhaust steam to said heating system, 90 means operative automatically to control the flow of steam to said engine in accordance with the requirements of the heating system, a source of power operating in parallel with said engine, and direct connections between 95 said supply and said heating system including pressure responsive means operative automatically when the engine fails to supply the desired quantity of steam to the heating system to deliver steam directly from said 100 supply to said heating system.

3. The combination with a high pressure steam supply and a low pressure heating system, of a steam engine connected to said supply and heating system to receive its steam from said supply and deliver exhaust steam to said heating system, means for controlling the flow of steam to said engine in accordance with the requirements of the heating system, a second steam engine, a common 105 load driven by said engines and governing means for the engines operative to cause the second engine to aid in carrying the load only when the first engine is unable to carry the load at the required speed.

4. The combination with a high pressure steam supply and a low pressure heating system, of a steam engine connected to said supply and said heating system to receive its steam from said supply and deliver exhaust 110 steam to said heating system, means for controlling the flow of steam to said engine in accordance with the requirements of the heating system, a second steam engine, a common load driven by said engines and independent speed governors for said engines, the governor for the first engine being set at a higher speed than the governor for the second engine.

5. The combination of a steam supply, a 130

steam heating system, a steam engine arranged to receive steam from said supply and deliver exhaust steam to said heating system, a valve responsive to changes in pressure in the heating system arranged to control the supply of steam to said engine in accordance with the requirements of the heating system, direct connections between said supply and said heating system including a pressure reducing valve operative automatically, when the engine fails to supply the desired quantity of steam to the heating system, to deliver steam directly from said supply to said heating system, a second steam engine, a common load driven by said engines, and speed governing means for the engines operative to cause the second engine to aid in carrying the load when the first engine is unable to carry it at the required speed.

6. The combination of a steam supply, a steam heating system, a steam engine connected to said supply and said heating system to receive steam from said supply and deliver exhaust steam to said heating system, means operative automatically to control the flow of steam to said engine in accordance with the requirements of the heating system, a load for said engine, and additional means operative automatically to carry any part of the load which said engine is unable to carry at the required speed.

7. The combination with a steam supply and a steam heating system, of a steam engine connected to said supply and heating system to receive its steam from said supply and deliver exhaust steam to said heating system, means for controlling the flow of steam to said engine in accordance with the requirements of the heating system, direct connections between said supply and said heating system including pressure responsive means operative automatically, when the engine fails to supply the desired quantity of steam to the heating system, to deliver steam directly from said supply to said heating system at substantially the pressure normally maintained on said system, a second steam engine, a common load driven by said engines and governing means for the engines operative to cause the second engine

to aid in carrying the load only when the first engine is unable to carry the load at the required speed.

8. A system of the character described, comprising a steam supply, a steam heating system, a steam engine arranged to receive steam from said supply and deliver exhaust steam to said heating system, a valve controlling the supply of steam to said engine, said valve being operative automatically to permit the engine to take only enough steam to satisfy the requirements of the heating system, a load for said engine, additional means operative to aid said engine in carrying the load, and governing means operative to cause said additional means and engine to carry said load at substantially constant speed.

9. The combination of a steam supply, a steam heating system, a steam engine arranged to receive steam from said supply and deliver exhaust steam to said heating system, automatic means controlling the flow of steam to said engine and arranged to allow the engine to take only enough steam to meet the requirements of the heating system, and speed governing means operative to control the flow of steam to said engine.

10. The combination of a steam supply, a steam heating system, a steam engine arranged to receive steam from said supply and deliver exhaust steam to said heating system, automatic means controlling the flow of steam to said engine and arranged to allow the engine to take only enough steam to meet the requirements of the heating system, speed governing means also operative to control the flow of steam to said engine, and additional means connecting said steam supply and said heating system and operative automatically when the engine fails to supply the desired quantity of steam to the heating system to deliver steam directly to said system.

In testimony whereof I have affixed my signature, in presence of two witnesses.

JOSEPH V. SANTRY.
